(57) **CLAIM**

The ornamental design for a protective sports spat for cleated or spiked sports shoes, as shown and described.

DESCRIPTION

FIG. 1 is a top view of a protective spat for cleated or spiked sports shoes showing our new design;

FIG. 2 is a bottom view thereof;

FIG. 3 is a side elevation view thereof, in use condition;

FIG. 4 is a bottom view thereof, in use condition; and,

FIG. 5 is an opposite side elevation view to that of FIG. 3, in use condition.

The showing of a shoe inserted in the protective sports spat for cleated or spiked sports shoes in FIGS. 3-5 is for illustrative purposes only and form no part of the claimed design.
